ATTORNEY

UNITED STATES PATENT OFFICE.

OMER BENJAMIN HUNTER, OF CHICKASHA, OKLAHOMA.

WATER TOP.

Application filed July 21, 1927. Serial No. 207,459.

This invention relates to amusement apparatus and more particularly to apparatus of this character for use in comparatively shallow water.

5 A primary object of the invention is to provide a whirlable anchored float capable of supporting heavy loads and which is especially adapted for use on beaches and in pools to afford amusement for bathers who climb 10 onto the float and during the whirling thereof endeavor to retain their positions on the float and avoid being thrown therefrom into the water and which operates similar to the rotating platforms used on land.

15 Another object of the invention is to construct an apparatus of this character equipped with air chambers to increase the buoyancy thereof.

In carrying out these objects, the invention 20 is susceptible of a wide range of modification without departing from the spirit or sacrificing any of the advantages of the claimed invention; there being shown in the drawings for illustrative purposes a preferred and practical form, in which—

Figure 1 is a perspective view of the apparatus in use;

Fig. 2 represents a vertical section of an apparatus embodying this invention taken on 30 a small scale;

Fig. 3 is a top plan view thereof, and

Fig. 4 is a detail perspective view of one form of anchor used.

The apparatus which may be constructed in 35 many different forms is here shown in the form of a float 1 comprising a platform 2 constructed of twelve gauge steel with all edges finished smooth, and which may be of any desired size, preferably about eight feet 40 in diameter, with an air chamber 3 located on its lower face and made in the form of an inverted cone formed on the lower face of the platform, said cone being preferably about two feet deep and seven feet six inches 45 in diameter and which while operating to provide buoyancy for the float also permits it to tilt according to the shifting of the weight on the platform. A platform of this size operates best in water about four to five feet deep but may be adjusted to water from 50 three feet six inches to five feet six inches in depth.

Extending through the platform and the apex of the cone 3 and made integral therewith or permanently fixed thereto in any

suitable manner, is a sleeve 4 which extends above the platform and below the cone. This sleeve 4 is in the form of a D. S. seamless steel tube about one and one half inches inside diameter and operates as a hub for the float which is designed to rotate on a shaft 5 which extends through the tube 4 and has a hand wheel 6 fixed to the upper end thereof while its lower end is connected by a universal joint 7 with an anchor 8. This anchor may be of any suitable or desired construction and is here shown in the form of a heavy rod bent in the form shown in Fig. 3 with the ends 9 and 10 thereof extended in opposite directions to form a secure connection with an anchor block 11 preferably constructed of concrete and of any desired shape and suitable size to ensure the anchoring of the float at the bottom of the water in which it is to be used. The block 11 is here shown rectangular and has embedded therein above the base of the anchoring member 8, a suitable reinforce in the form of bars 12 arranged to intersect each other and thereby securely hold the anchor in the block.

The shaft 5 is preferably about one and three eighths inches in diameter and seven feet long.

A sleeve 13 one and one-half inches diameter and about twelve inches long encircles the upper end of the shaft 5 and is riveted thereto directly under the hand wheel 6 when installed. This wheel 6 is secured to the shaft 5 by any suitable means a set screw 14 and a key 15 being here shown for this purpose. The handwheel may be either in the form of a disk or have spokes as here shown.

A rubber tube 16 about two inches and a half in diameter and eighteen inches long 95 covers the working parts between the handwheel and the platform and protects them.

The platform is shown with a rolled reinforced rim 17 and with oval cleats 18 radiating from the center of the platform and having their ends flattened and welded to the rim.

In the use of the apparatus as here shown the hand wheel 6, being fixed to the shaft and the latter connected with the anchor, the passengers or parties using the apparatus and who are mounted on the platform grasp the hand wheel in hand over hand fashion thereby causing the platform to rotate and the shifting of the positions of the persons 105 110

on the platform will cause it to tilt and deposit its load into the water. The universal joint connection between the shaft 5 and anchor 8 eliminates friction and at the same time permits the platform to tilt as well as rotate producing a gyrating movement which greatly increases the thrill of the passengers.

It is to be understood that the platform may be anchored by any suitable means, one embodiment only being herein shown.

Without further description it is thought that the features and advantages of the invention will be readily apparent to those skilled in the art, and it will of course be understood that changes in the form, proportion and minor details of construction may be resorted to, without departing from the spirit of the invention or its scope as claimed.

20 I claim:—

1. The combination of an anchor, an upright shaft having a universal connection with said anchor, a float mounted to rotate on said shaft, and comprising a platform 25 having an inverted cone shaped air chamber on the bottom thereof through the

apex of which and the center of the platform said shaft extends, and a hand grip fixed to said shaft to provide for the rotation of the float by users of the device changing 30 their hand holds on said grip.

2. The combination of an anchor, an upright shaft having a connection with said anchor, a platform mounted to rotate on said shaft and having an inverted cone-shaped 35 air chamber on the bottom thereof through the apex of which and the center of the platform said shaft extends, to provide maximum buoyancy for the platform with a minimum resistance, and means for rotating the 40 platform.

3. The combination of an anchor, an upright shaft having a connection with said anchor, a float mounted to rotate on said shaft and having an inverted cone-shaped 45 air chamber on its bottom through the apex of which and the center of the float said shaft extends, and a hand grip fixed to said shaft to provide for the rotation of the float by users of the device changing their hand hold 50 on said grip.

OMER BENJAMIN HUNTER.
